H. M. JOHNSON

COIN CONTROLLED OPTICAL INSTRUMENT

Filed Nov. 13, 1924

Fig. 5. Fig. 4 Inventor:

Herman M Johnson
Heisley & Ramsey

Attorney

UNITED STATES PATENT OFFICE.

HERMAN M. JOHNSON, OF PORTLAND, OREGON.

COIN-CONTROLLED OPTICAL INSTRUMENT.

Application filed November 13, 1924. Serial No. 749,652.

My invention relates to coin controlled optical instruments which are to be placed at the disposal of the general public, at points of scenic interest. Heretofore, all devices of this character, with which I am familiar, have either been very complicated or have required mechanism which is so expensive that the capital necessarily outlaid does not produce a reasonable revenue from the persons using said glasses, because only a small charge is made for each use.

The object of my invention is to provide simple coin-controlled means for locking the optical instruments in inoperative position, whereby the instrument is rendered normally inoperative, in that it is held immovable, pointed towards a surface of the supporting means of the instrument, and thus cannot be pointed at any object; but when a coin of a predetermined denomination is deposited in the lock, the latter is released and the optical instrument may then be pointed to the object to be viewed; and upon the user of the instrument returning the same to its original position, it again becomes automatically locked in place, and inoperative.

I attain my object in a device comprising a base, or other support, including spaced arms, an optical instrument pivotally carried by said base or support, so that it may be pointed at the object to be viewed, means for locking said instrument in position facing said base or surface thereof, thus rendering the instrument inoperative; and coin controlled means for releasing said locking means, whereby upon the insertion of a certain coin in said locking means the instrument is released, so that it may be properly manipulated; and said locking means being again rendered active by the act of the user of the instrument returning the same to its initial position.

Another object of my invention is to provide mechanism by which the instrument used serves also as an operating lever, that is, when a coin is placed in the receptacle provided, the lifting of the instrument will serve to release the mechanism by means of said coin.

A further object is to provide a device of this character with parts so arranged that one part cannot be removed from the other nor can the mechanism be opened except by means of a proper coin.

The above mentioned features are herein

after fully described in greater detail, reference being made to the accompanying drawings, in which:

Fig. 1 is a section taken substantially on the line 1—1 of Fig. 2, some of the parts being broken away to disclose details of construction;

Fig. 2 is a section taken substantially on the line 2—2 of Fig. 1;

Fig. 3 is a plan section taken substantially on the line 3—3 of Fig. 1;

Fig. 4 is a diagrammatic fragmentary view of a portion of the mechanism and shows the co-operative relationship of the parts;

Fig. 5 is an elevation of one of the parts thereof.

In my invention the instrument which is shown in the drawings and which is controlled by the coin operated mechanism, is a pair of binoculars which is mounted between two hollow supports 2 and 3 which are carried by a hollow rotatable base 4. Within said base 4 is enclosed all of the operative mechanism of my invention. Said base is carried upon a trunnion 5 carried by a fixed ledger or shelf 6. Said trunnion extends through the bottom of said base 4, and the base has an upstanding flange 4^a about said trunnion, which is slightly shorter than the portion extending into said base and thus a pin 7 can extend diametrically through said trunnion and overlie the top of said upstanding flange thus preventing the hollow base 4 from being removed from the fixed ledger or shelf 6. Said instrument 1 is carried by trunnions 8 and 8^a at each side, the trunnion 8 having a spherical end 9 which is mounted in suitable bearings 10 within the hollow support 2. Said bearings 10 are tightened by a screw 11 which extends up through said hollow support and which can be manipulated from within the hollow base at a point adjacent the door 12 in said base.

The end of the trunnion 8^a is provided with a pulley 13 to which one end of the flexible cord 14 is fastened. Said cord is mounted over the periphery of said pulley and extends centrally through the hollow vertical support 3. A suitable guide 15 is provided at the lower end of the vertical support 3 to hold the cord in substantial alignment with said hollow support. The other end of said flexible cord is fastened to

and mounted over a pulley 16 carried by the shaft 17 which is carried between two spaced bearings 18 fastened to the hollow base 4.

A disc 19 is also carried by said shaft 17 and has a projection 20 on its face which engages a rockable member 21 which tends to stop said disc in a predetermined position. In this position, a slot 19^a for the coin 22 which actuates the device, is arranged in vertical alinement with the receptacle 23 provided for the coin.

Said rockable member 21 is held in engagement with said projection 20 by a spring 24. Said rockable member 21 carries a control finger 25 which extends about said rotatable disc 19 to a point adjacent the slot 21, in its normal position. The end of said control finger is arranged so as to be lifted by a predetermined coin 22, when said disc 19 is rotated by a movement of the instrument being controlled.

Spring 26 tends to hold said finger in such a manner that the projection 25^a engages a shoulder 27 formed upon the disc 19. A box 28 within said hollow base receives the coin 22 from the slot 19^a after said disc is rotated and has lifted said finger 25. Said box 28 is provided with a stop receiving means 28^a. A cam-shaped member 29 engages the rockable member 21 each time said disc 19 is rotated and rocks said member about its pivot 30 in such a manner as to actuate the counter 31 once each time said instruments are lifted.

The operation of my invention is as follows:

When it is desired to use said instrument, a coin 22 is placed in the receptacle 23 and allowed to fall into the slot 19^a. With the coin in this position, the instrument 1 can be rotated about a horizontal axis to substantially horizontal position, and thus can be used to view the surrounding landscape. The coin 22 strikes the underface of the finger 25 and lifts it to such a degree that the projection 25^a clears the shoulder 27 to prevent their engagement. As said disc is rotated by the movement of said instrument through said flexible cord, the projection 29 engages one end of said rockable member 21 and rocks the same about its pivot 30 to actuate the counter member 31.

I claim:

1. In a device of the character described, a base, spaced vertical supports carried by said base, an optical instrument carried by said supports, means for locking said instrument in position facing said base which thus serves as a shield therefor, coin controlled means for releasing said locking means, said locking means being reset by a movement of said instrument to its original position.

2. In a device of the character described, a base adapted for rotation about a vertical

axis, an optical instrument carried by said base mounted for adjustment to two positions, means for locking said instrument in position facing said base which thus serves as a shield therefor, coin controlled means for releasing said locking means, said locking means being reset by a return movement of said instrument towards its original position.

3. In a device of the character described, a base mounted for rotation about a fixed axis, spaced supports carried by said base, an instrument carried by said supports, said optical instrument being mounted for rotation about an axis normal to that about which said base rotates, means for locking said instrument in position facing said base which thus serves as a shield therefor, coin controlled means for releasing said locking means, said locking means being reset by a return movement of said instrument to its original position.

4. In a device of the character described, a base, spaced supports carried by said base, an instrument carried by said supports, means for locking said instrument in one position, coin controlled means for releasing said locking means, a rockable member cooperating with a rotatable part of said locking means, said rockable member acting as a stop to position said locking means.

5. In a device of the character described, a base, spaced supports carried by said base, an instrument carried by said supports, means for locking said instrument in one position, coin controlled means for releasing said locking means, said locking means being reset by a movement of said instrument relatively to said supports, a rockable member cooperating with a rotatable part of said locking means, said rockable member acting as a stop to position said locking means, means on said rotatable part of said locking means adapted to engage said rockable member when said instrument is rotated relatively to said supports.

6. In a device of the character described, a base, spaced supports carried by said base, an instrument carried by said supports, means for locking said instrument in one position, coin controlled means for releasing said locking means, a rockable member cooperating with a rotatable part of said locking means to limit the rotation thereof in one direction, and a counter actuated by each move of said rockable member.

7. In a device of the character described, a base, spaced supports carried by said base, an instrument carried by said supports, one of said supports being hollow, means for locking said instrument in one position, coin controlled means for releasing said locking means, the first mentioned means being connected to said instrument by means of a flexible cord passing through said hollow

support and fastened to that end of said instrument extending into said hollow support.

8. In a device of the character described, 5 a rotatable hollow base, spaced, vertical, hollow supports carried by said base, an instrument carried by said supports, means within said hollow supports for locking the said instrument to said supports, means for 10 locking said instrument in one position, said

means being connected to said instrument by means of a flexible cord passing through one of said hollow supports and fastened to that end of said instrument extending into said hollow support, coin controlled means 15 for releasing said locking means, said locking means being reset by a movement of said instrument relatively to said supports.

HERMAN M. JOHNSON.
